UNITED STATES PATENT OFFICE

99,499

DESIGN FOR A LAUNDRY BAG

Bennett C. Creed, Hinsdale, Ill.

Application December 3, 1934, Serial No. 54,232

Term of patent 3½ years

To all whom it may concern:

Be it known that I, Bennett C. Creed, a citizen of the United States, residing at Hinsdale, in the county of DuPage and State of Illinois, have invented a new, original, and ornamental Design for a Laundry Bag, of which the following is a specification, reference being had to the accompanying drawing, forming part thereof.

In the drawing—

Fig. 1 is a front view of a laundry bag showing my new design, the dominant feature of which resides in having the extreme width of the laundry bag near the bottom of the trousers.

Fig. 2 is a rear view thereof.

I claim:

The ornamental design for a laundry bag, as shown and described.

BENNETT C. CREED.
